UNITED STATES PATENT OFFICE.

PHILIP H. LONG, OF NEWARK, NEW JERSEY.

DESIGN FOR A HANDLE FOR BUTTON-HOOKS.

SPECIFICATION forming part of Design No. 27,590, dated August 31, 1897.

Application filed July 15, 1897. Serial No. 644,735. Term of patent 7 years.

To all whom it may concern:

Be it known that I, PHILIP H. LONG, a citizen of Great Britain, residing at Newark, in the county of Essex and State of New Jersey, have invented and produced a new and original Design for Handles for Button-Hooks, Manicure Articles, &c.; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

15 The single figure of the drawing is a plan of a button-hook having a handle of the new design.

As shown in said drawing, the leading or material feature of my design consists of the outline of the handle in plan, which includes the opposite ogee curves at the sides of the handle and scallops at and near the end thereof, the series of marginal bead-like ornaments conforming to the marginal outlines, 25 and the scroll-shaped ornaments at the scalloped end of the handle and about midway between the ends.

As indicated in said drawing, *a* indicates

the handle. *b* indicates the long ogee curves at the opposite sides of the handle, the curved 30 outlines being somewhat concaveous at or near the shank-like part of the handle, as at *b'*, from which they gradually curve outwardly and oppositely, as at *b''*, at the swell in the handle. Near the broader end of the handle 35 the opposite outlines are concave, as at *b'''*, and at said end the said handle is scalloped, as at *c c c*, the series of scallops extending around said end. On the face of said handle at the margins are series of bead-like ornaments *d*, the continuity of which is interrupted near the middle of the handle by scroll-shaped ornamentation *e*, and at the end of the handle near the scallops *c* are scroll-shaped ornamentations *f*. 45

What I claim as new is—

The design for a handle for button-hooks, manicure articles, &c., substantially as shown and described.

In testimony that I claim the foregoing I 50 have hereunto set my hand this 9th day of July, 1897.

PHILIP H. LONG.

Witnesses:

CHARLES H. PELL,
C. B. PITNEY.
